United States Patent Office.

WILLIAM S. ANDERSON, OF SHELBYVILLE, TENNESSEE.

Letters Patent No. 80,584, dated August 4, 1868.

IMPROVED CAR-COUPLING.

The Schedule referred to in these Letters Patent and making part of the same.

TO ALL WHOM IT MAY CONCERN:

Be it known that I, WILLIAM S. ANDERSON, of the town of Shelbyville, county of Bedford, and State of Tennessee, have invented a new and useful machine, viz, a combination for saving and coupling railroad-cars, to be known by the name of the "Independent Self-Coupling Machine" for railroad-cars, combined with the car-saving machine; and I do hereby declare that the following is a full and exact description of the construction and operation of the same, reference being had to the annexed drawings, making a part of this specification, in which—

Figure 1 is an inside view, and

Figure 2 a front view of the independent self-coupling machine; and

Figure 3 is a front view of the car-saving machine when ready for use, and

Figure 4 is a side view of the same, and

Figure 5 is a centre view when broken.

To enable others skilled in the art to make and use my invention, I will proceed to describe it.

I. The independent self-coupling machine.

The frame that receives the coupling-plate or "coupler," which is also the car-saving machine, and represented by the letter F, is an oblong square, represented by the letter A, and is to be fastened to the end of each car, and at one end has an opening, into which the coupler attached to the advancing car enters, and is made secure, as hereafter described, and upon this is planted a perpendicular frame, letter B, in which is the coupling-machine, letter C, and consisting of the following parts, and located as follows when ready to "receive the coupler." The lower part consists of a square block, which is attached to the upper block by a hinge opening out in an angle in the back side of the perpendicular frame, and forming a mitre-joint at the centre of the hinge, letter B, and the lower end of this block resting immediately opposite the opening in the frame, letter A, and the two blocks combined constitute a lock-lever.

Through the centre of the upper block is a mortise, through which, with the opposite sides of the frame, passes a rod, upon which the lever plays up and down, making its angles, and at the upper end of this block is a mitre, and attached to it is another block, styled "bolt-bearer," letter D, passing horizontally through the upper part of the front side of the perpendicular frame, letter B, to which is attached, at this opening in the frame, one end of a spring, the other being fastened to the inside of the front of the frame, letter B.

Passing along the outside of the front of the frame, letter B, is a bolt, letter E, at the upper end of which is a head resting upon the bolt-bearer, with a piece of iron fastened to the head, and passing through a mortise in the front top of the frame to the top of the car, the bolt, passing perpendicularly down from the "bolt-bearer" through a block fastened to the perpendicular frame, and then through the upper side of frame, letter A, rests over the opening to receive the "coupler," as above described.

Now, with the parts described, as the machine stands ready to receive the coupler, letter F, I proceed to describe how it acts when the coupler, attached to an advancing car, enters the opening in frame A.

One end of the coupler being attached to the advancing car, the other end is then so elevated as to pass through the opening in frame A, the mortise in the coupler being immediately under the lower end of the bolt above described, and, striking the lower end of the lower block of the within machine, as above described, forces it back, thereby causing the spring attached to the "bolt-bearer" to force in the bolt-bearer, so as to relieve the bolt resting upon it as above described, and permitting it to drop until the head rests upon the block, through which it passes just below the bolt-bearer, the lower end passing perpendicularly through the opening in frame A, and through the mortise in the coupler, thus fastening securely the two cars. If, then, you wish to relieve the cars, it can be done from the top of the car by raising the bolt E by the piece of iron attached to its head, as above described, without danger to any one, and the coupler will then slip out and remain attached to the receding car.

II. The car-saving machine.

This consists of the above coupler, which consists of two equal parts, which are locked in the centre by side or dove-tailed tenons, with mitre-joints. Immediately above where these two pieces are united is a clasp, which is fastened sideways and lengthways to the coupler, and with a bolt passing through the clasp and each one of these pieces, and fastened on the opposite side, the bolts and clasps being sufficiently strong to hold the pieces together for all practicable purposes.

Now, it is claimed for this invention that it will save the cars attached to a train in motion in this way, that if one of the cars, when in motion, should break down, its weight would break the bolt and clasp and sunder the pieces of the coupler, thereby relieving the cars in front of the one breaking; or, if one of the cars should be thrown from the track, its ponderous weight would again sever the pieces, relieving the rest of the train, and thereby keeping it on the track, so that whether it be a side or perpendicular face, the weight of the car would wrench apart the pieces, and relieve the other.

What I claim, and desire to secure by Letters Patent, is—

The combination of the "lever C," "bolt-bearer D," "bolt E," and "link F," in connection with the "buffer A" and "coupling-frame B," secured to the car by the "bolt H," all constructed and arranged as described, and for the purpose specified.

WILLIAM S. ANDERSON.
